UNITED STATES PATENT OFFICE

WALLACE C. MILLS, OF ROCKFORD, ILLINOIS, ASSIGNOR TO J. L. CLARK MANUFACTURING CO., OF ROCKFORD, ILLINOIS, A CORPORATION OF ILLINOIS

CLOSURE

Application filed November 7, 1927. Serial No. 231,627.

My invention relates to closures for cans, packages or the like which are adapted to contain powdered substances. More particularly it relates to such closures having a plurality of sifter openings and a large opening for pouring, with means for selectively opening either of the two.

The primary object of the invention is to provide a novel closure having a single slide member for opening and closing either sifter or pouring openings.

Another object is to provide such a closure which is of very simple construction, which may be easily assembled, in which the handle or engaging means on the slide is positioned to be readily accessible at all times, and in which the slide is held and guided by means formed from the main closure wall.

Other objects and advantages will become apparent from the following description and from the accompanying drawings in which:

Figure 1 is a plan view showing the top of a can embodying the preferred form of the invention.

Fig. 2 is a fragmentary sectional view taken along the line 2—2 of Fig. 1.

Fig. 3 is a fragmentary sectional view taken along the line 3—3 of Fig. 1.

Fig. 4 is a fragmentary sectional view showing an alternative construction.

The exemplary embodiment chosen for disclosure herein is shown as applied to a can 5 and comprising generally a main closure wall 6 and a slide member 7 mounted thereon.

The wall 6 is preferably attached permanently to the upper edges of the can 5 by means of a seam 8 or other suitable crimping of the two parts.

The slide member 7 is preferably associated with the wall 6 in such a manner that it may be moved in either of two directions selectively to open either a pouring opening or sifter openings. For the purpose of associating the slide member 7 with the wall 6 a pair of spaced parallel slits 10 are formed

in the wall 6, and the metal between the slits is offset downwardly from the plane of the wall.

For a purpose which will hereafter appear an aperture 11 is formed in the struck down portion of the wall 6 in such a position as to leave two strips 12 of substantial width, one between the aperture 11 and each of the slits 10, and to leave a ledge 13 on the other two sides of the aperture.

The width of the slide 7 is substantially the same as the length of the slits 10 so that the slide 7 may pass therethrough and in its operative position the middle portion of the slide 7 lies above the two ledges 13 and the two strips 12 while the end portions thereof pass through the slits 10 and lie below the wall 6.

In order that the slide 7 may be easily engaged for movement, a finger-piece 14 is provided which, in the form illustrated in Figs. 1, 2 and 3, comprises a rib in the form of a transverse fold of metal formed from the body of the slide 7 centrally thereof and extending upwardly therefrom. In this form it is desirable to have all of the openings closed when the finger-piece 14 is positioned midway between the slits 10. To this end a pouring opening 15 and a plurality of sifter openings 16 are formed in the slide 7 so that when the finger-piece 14 is centrally positioned the pouring opening 15 will lie above one of the strips 12 and be closed thereby while the sifter openings 16 will lie above the other of the strips 12 and will be closed thereby.

In the alternative form illustrated in Fig. 4 a different form of finger-piece is employed which is formed from the metal which is removed from the slide 7 to form the pouring aperture 15. This is done by severing the metal only on the two sides of the aperture 15 and the end nearest the end of the slide, thus leaving a strip of metal which may be formed into a roll or curl 20 which extends upwardly from the slide 7. The use of this form of finger-piece necessitates only a slight

change in the proportioning of the elements and results in an added economy since it uses metal which would otherwise be wasted.

To open either the pouring opening 15 or the sifter holes 16 the slide 7 is moved by means of the finger-piece 14 until the desired opening lies over the aperture 11 in the wall 6 and the other opening lies below the wall 6 and is closed thereby.

In constructing the preferred embodiment illustrated in Figs. 1, 2 and 3, so that the slide 7 may be easily placed in its operative position, its length is preferably made slightly less than twice the distance between the slits 10 thus making it possible to insert the slide without bending. When so proportioned, stops 17 are provided which extend downwardly from the wall 6 into the path of the slide 7 so that the slide is stopped when the holes therein are in position above the aperture 11 in the wall 6.

The alternative embodiment shown in Fig. 4, is also proportioned so the parts may be easily assembled and so that the walls of the 25 can serve to perform the function of the stops 17 shown in the preferred form.

It will be apparent from the foregoing description that in the closure provided a single slide member serves to provide sifter and 30 pouring openings and that this slide is held in place by means formed from the main closure wall. It will also be apparent that the arrangement and proportioning of parts herein shown provides a closure which is easily assembled and which is readily operable due to the accessibility of the finger-piece.

I claim as my invention:

1. A receptacle closure comprising a wall having two parallel slits formed therein and the metal between said slits offset downwardly from the plane of said wall, said wall having a single discharge opening formed in said offset portion, and a slide member having its opposite ends passing through said slits and having pouring and sifter openings formed in spaced relation therein so as to be movable selectively into registry with said discharge opening.

2. A receptacle closure comprising a wall having two parallel slits formed therein and a discharge opening formed between said slits, a slide member having its opposite ends extending through said slits and having pouring and sifter openings formed in 55 spaced relation therein adapted to be selectively brought into registry with said discharge opening by moving said slide in opposite directions, said slide having a transverse upwardly extending finger-piece 60 formed thereon near its center to provide for moving said slide.

3. A receptacle closure comprising a wall having two parallel slits formed therein and the metal between said slits offset downwardly from the plane of said wall, said wall

having a single discharge opening formed in said offset portion, a slide member having its opposite ends passing through said slits and having pouring and sifter openings formed in spaced relation therein so as to be movable selectively into registry with said discharge opening, and means for limiting the movement of the slide in either direction.

In testimony whereof, I have hereunto affixed my signature.
